(57) **CLAIM**

The ornamental design for a wire feeder enclosure, as shown and described.

DESCRIPTION

FIG. 1 is a front perspective view of a wire feeder enclosure for a wire feeder;

FIG. 2 is a rear perspective view of the wire feeder enclosure of FIG. 1;

FIG. 3 is a left side view of the wire feeder enclosure of FIG. 1;

FIG. 4 is a right side view of the wire feeder enclosure of FIG. 1; and,

FIG. 5 is a top plan view of wire feeder enclosure of FIG. 1. The broken lines shown in the Figures are for illustrative purposes only and form no part of the claimed invention.
